PLUG RETAINING PLATE FOR LOCK CYLINDERS

Harry E. Soref and Daniel J. Foote, Milwaukee, Wis., assignors to Master Lock Company, Milwaukee, Wis., a corporation of Wisconsin

Application July 18, 1947, Serial No. 761,862

4 Claims. (Cl. 70—367)

1

This invention relates to improvements in plug retaining plates for lock cylinders.

In certain types of locks the body or casing contains a cylinder assembly into which the lock key is inserted for operating the lock. The cylinder assembly includes a pin-carrying shell having revolvably mounted therein a cylindrical plug which receives the key for the purpose of actuating the pins. In conventional lock structures of the type under consideration the outer end of the lock casing is closed by a plate having an opening therein registering with and of slightly greater diameter than the cylindrical plug of the cylinder assembly. In a construction of this character axial displacement of the shell of the cylinder assembly is prevented by a bottom plate which bears against the end of the shell, thereby holding the shell but permitting the plug to have a necessary limited axial movement relative to the shell. However, displacement of the plug and undue axial movement thereof is prevented solely by a washer secured within a shouldered groove on an inner extended portion of the plug and bearing against the inner end of the shell.

In the conventional arrangements described, the washer serves as the sole instrumentality for holding the cylinder assembly in its correct relationship and during continued manipulation of the lock and removal of the tight fitting key from the lock plug, the washer is subjected to considerable stress and strain, and should the washer eventually become worn or defective, the inner plug of the cylinder assembly can slip entirely out of the shell and thus render the lock inoperative.

With further respect to the conventional lock structures of the type cited, the washer-retaining arrangement between the plug and the shell is such that too little axial movement between the plug and shell is permitted which often results in misalignment of the plug holes with relation to the shell-carried pins, causing the pins to be blocked and wedged so that proper operation of the lock mechanism is impaired. Additionally, in the conventional structures, lock picking is possible, as pressure may be put onto the pins to block them.

With all of the foregoing considerations in mind, it is a primary object of the present invention to provide a plug-retaining plate for a lock cylinder which eliminates the objections mentioned in connection with conventional cylinder lock structures through the provision of a retaining plate construction which bears on the outer end of the plug to prevent displacement of the plug relative to the cylinder shell while per-

2

mitting slight desirable and necessary play of the shell relative to the axially fixed plug.

In lock constructions of the type under consideration, the keys engage the cylinder assembly plugs quite tightly, and considerable pull must be exerted on a key in removing it longitudinally from the cylinder assembly, and it is therefore, a further object of the invention to provide a lock cylinder retaining plate, which, while firmly holding the plug against axial movement, permits the cylinder shell to find its own alignment, thereby facilitating the action of the lock pins and removal of the key.

A further object of the invention is to provide, in a lock construction of the class described, a plug retaining plate which eliminates pressure, strains and wear on the washer which is interposed between the plug and shell of the cylinder assembly.

A further object of the invention is to provide a lock construction of such a nature that it is very difficult to pick the lock, as it prevents pressure being applied to the pins in the cylinder assembly for the purpose of blocking the pins.

A further object of the invention is to provide a lock construction of the class described wherein wedging and binding as between the plug and shell is eliminated and which facilitates operation and movement of the cylinder assembly.

A further object of the invention is to provide a plug-retaining plate for a lock cylinder which is of very simple construction, is strong and durable, is inexpensive, and is well adapted for the purposes set forth.

With the above and other objects in view, the invention consists of the improved plug-retaining plate for a lock cylinder and its parts and combinations, as set forth in the claims, and all equivalents thereof.

In the accompanying drawing in which the same reference characters indicate the same parts in all of the views:

Fig. 1 is a longitudinal sectional view of a lock having the improved plug-retaining plate, parts being broken away and in section;

Fig. 2 is a bottom or outer end view of the lock as shown in Fig. 1; and

Fig. 3 is an enlarged fragmentary detail sectional view of the interior of the lock assemblage showing the cylinder shell and plug and the relation of the plug-retaining plate thereto.

While the invention has been illustrated as being embodied in a padlock, it is to be understood that the plug-retaining plate structure is applicable to cylinder locks generally and may be

used, not only in connection with padlocks, but with door locks, automobile locks, and other types of cylinder locks.

Referring now more particularly to the drawing, the lock body or casing is indicated by the numeral 5, and the interior of the same has partitions and walls to define cavities for certain of the lock mechanisms. As is conventional in locks of this type, there is mounted in the body and extending outwardly of the inner or upper end thereof, a shackle 6 having an extension arm portion 6' thereof extending into a cavity in the body 5 and being mounted on a shackle spring 7 to permit yielding reciprocatory movement of the shackle, when released, and swinging movement thereof. The shorter arm portion 6" of the shackle is adapted, for locking purposes, to enter another cavity in the body and to have a shouledered portion 8 thereof entered by a spring urged lock lever 14. The latter is set and released by means of the mutilated projecting inner end portion 9' of a slotted cylindrical plug 9 forming part of a cylinder assembly, which assembly also includes a slotted shell 10. The shell 10 is of less length than the plug 9 and encloses the plug in a manner so that the plug may turn in the shell, with the shell being anchored against turning movement by a lateral extension portion 10' on the shell, confined within a suitable recess therefor in the body 5. The slotted portions of the shell and shell extension 10' have reciprocatably mounted therein, against springs 11, a series of pins 12 which, when the assemblage is locked, enter openings therefor in the plug 9 but which, when a proper key 13 is inserted into the slot 15 therefor in the plug, are disengaged from the plug holes so as to permit turning movement of the plug 9 relative to the shell 10 for causing the plug mutilated inner end 9' to operate the lever 14.

From Figs. 1 and 3, it will be observed that an inner portion of the plug 9, just beyond the inner end of the shell 10, is provided with an annular groove or recess 16 in which there is seated a retaining ring or washer 17. In prior lock structures of the type under consideration, a similarly positioned washer was the sole means for preventing axial displacement of the plug relative to the cylinder shell. However, as will hereinafter appear, in the present invention the washer 17 simply forms an instrumentality for holding the plug 9 and shell together as a unit and reliance is not placed on the washer 17 as the means for preventing axial displacement of one of the cylinder assembly members relative to the other. In actual practice, there should be slight play of the washer 17 in its groove 16 so that the shell may make its proper alinement relative to the plug for freer action of the pins 12 and facilitation of removal of the key 13.

In the present invention great importance is attached to a specially formed retaining plate 18 secured to the lower or outer end of the casing 5 and its association with the plug 9 of the cylinder assembly. Said plate 18 is secured to the lock body or casing 5 by any convenient means such as by rivets or pins 19. There is formed in the inner face of the plate 18 and concentric with the cavity for the shell 10, a circular opening 20 of greater diameter than the lower or outer end of the plug 9 which projects thereinto. The plate opening 20 does not, however, extend entirely through the plate 18, but the outer stock of the plate 18 is formed with a reduced opening 21 of less diameter than the adjacent end of the plug 9 and the metal of the plate 18 surrounding

said reduced opening 21 is extruded or pressed outwardly slightly so as to define an annular collar 22 for the opening 21 with the inner face of said collar forming an annular shoulder 23 on which the outer end of the plug 9 firmly seats. Obviously, the arrangement of the plate 18, as described, is such that the annular shoulder 23 engages the outer end of the plug 9 and prevents axial movement of the plug, thereby anchoring the plug against any possible axial displacement but permitting the surrounding shell 10 to axially shift, if necessary. The reduced opening 21 is sufficiently large to easily receive the shank of the key 13. In practice, a key fits rather tightly within the plug 10 in engagement with the operated pins 12 and to withdraw the key 13 from the lock, considerable pull must be exerted on the key. By virtue of the present improvements, this may be done without straining the cylinder assembly and without imposing any stress on the washer 17 because the plug 9 is in abutment with the shoulder 23 of the plate 18 which takes all longitudinal forces.

In the improved lock structure, considerable advantage is found in anchoring the plug 9 against longitudinal or axial movement and permitting the necessary slight axial movement for pin alinement to be accomplished through the floating of the surrounding shell 10. Any possibility of wedging or binding as between the plug and shell is thereby eliminated and the movement of the shell permits the pins 12 to readily aline with the plug holes. With a lock constructed according to the present invention, picking of the same is very difficult because, due to the anchored plug, it is very difficult to put pressure on the lock pins 12 to block them.

The improved plug retaining plate for lock cylinders is extremely simple and inexpensive to manufacture, is easily mounted on the lock body to form an integral part of the lock assemblage, and is well adapted for the purposes described.

What we claim as our invention is:

1. In a lock having a casing with a cavity 45 therein which opens through an end of the casing, a pin shell non-rotatably mounted in said cavity, a plug turnable within said shell, means connecting the shell and plug as a unit and permitting slight longitudinal movement of the shell relative to the plug, and an apertured plate secured to said end of the casing and engaging the outer end of the plug to hold it against longitudinal movement while permitting slight longitudinal movement of the shell within said cavity.
2. In a lock having a casing with a cavity 50 therein, a cylinder assembly operatively mounted within said casing cavity, said cylinder assembly including a shell and a key-receiving plug turnable within the shell, and a plate secured to said casing, an intermediate portion of said plate having a shouldered aperture therein in which the outer end of said plug is seated and retained against outward longitudinal movement.
3. In a lock having a casing with a cavity 65 therein, a pin shell non-rotatably mounted in said cavity, a key-operated plug turnable within said shell and having its outer end extended beyond the outer end of the shell, means turnably connecting the shell and plug as a unit and permitting slight longitudinal movement of the shell relative to the plug, and an apertured plate secured to an end of the casing and engaging the extended outer end of the plug to hold it against longitudinal movement.
4. In a lock having a casing with a cavity 70

therein, a pin shell non-rotatably mounted in said cavity, a key-operated plug turnable within said shell and having its outer end extended beyond the outer end of the shell, the shell being susceptible of slight reciprocatory movement relative to the plug for pin alining purposes, and a plate secured to said casing, an intermediate portion of said plate having a shouldered opening therein in which the outer extended end of the plug is seated and through which a key may be inserted into said plug.
